ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

INSULATOR.

1,360,352.

Specification of Letters Patent. Patented Nov. 30, 1920.

Original application filed May 29, 1916, Serial No. 100,481. Divided and this application filed August 12, 1918. Serial No. 249,416.

To all whom it may concern:

Be it known that I, ARTHUR O. AUSTIN, a citizen of the United States, residing at Barberton, in the county of Summit and State of Ohio, have invented certain new and useful Improvements in Insulators, of which the following is a specification.

This invention relates to insulators in which one or more of the parts have connected surfaces roughened or sanded to provide means for cementing the parts together, and at the same time to permit greater resiliency between them.

The invention consists in the novel construction, combination and arrangement of the several parts.

In the drawings—

Figure 1 is a view partly in section of an insulator constructed in accordance with the principles of this invention.

Fig. 2 is an enlarged detail of a portion of the construction shown by Fig. 1.

Fig. 3 is a detail showing the edge of the metallic shell coated with yielding material.

Fig. 4 shows the adjacent portion of the insulating member so coated; and

Figs. 5 and 6 are detail views showing projecting particles attached to the insulating member.

This application is a division of my prior application, Serial No. 100,481, filed May 29, 1916, and patented November 19, 1918, No. 1,284,975. The present invention relates more particularly to an insulator made up of a number of parts, one or more of which are not insulating material, but are preferably of metal so that this application is limited to an insulator in which the insulating member formed with a sanded attaching surface is connected by cement to one or more metal parts.

In insulators which consist of a number of parts, either of similar or different materials, it is customary to unite the several parts by means of cement. The surfaces which are so connected may be knurled or roughened for affording anchoring surface for the cement, and thereby connecting the parts more rigidly together, but if the parts are too rigidly joined they may be subjected to undue stresses and strains caused by changes in temperature and other conditions which impair, rather than improve the insulators. The unglazed surfaces either pro-

vided with grooves, or made plain, may give fairly satisfactory results, but there are certain conditions which it is desirable to obtain in insulators, which can be better obtained if the surfaces are coated with glaze, not only where they are exposed to the weather, but also where they are in contact with cement. Cement, however, does not adhere readily to a glazed surface on account of its extreme glassy condition, and therefore to glaze the surface to be cemented while still maintaining the grooves in the surface, might give undesirable properties to the porcelain insulator, namely, increased electrical resistance, but it would produce a mechanically weak joint which would soon break apart or loosen up on account of the cement not adhering to the surface.

To overcome this mechanical and physical weakness, and to secure the properties which are desired in an insulator, it is found practicable to coat the surfaces of the insulating material to be connected before the insulating member is fired in the kiln with material which will produce a glazed surface, and while this coating is still wet, to sprinkle sand or crushed material which has, or has not been vitrified, but which will adhere to this coating on account of it being in a moist and sticky condition when the particles are first applied. Crushed unvitrified clay or sand is preferable, for the reason that if the material applied to the body of the insulating member has about the same coefficient of expansion and contraction in firing as the insulating member itself, there will be less tendency for the particles to chip or break after removal from the kiln.

When insulating members are thus prepared and are then placed in the kiln and vitrified, it is found that the insulating member itself is practically covered with glaze, thus giving a surface which adds to the electrical resistance, and prevents the absorption of moisture, but leaves the points of the applied material, or particles thereof projecting above the glaze and these points may be practically free of glaze at the outer ends, or entirely covered, the bases and sides of the particles being held firmly in the glaze and forming a substantial continuation of the insulating member itself.

Before assembling the insulator parts which are so formed, the roughened surfaces

are coated with an elastic or yielding material, which may be spread upon the surface in any convenient manner, as for example, by dipping the portion of the insulator to be 5 coated into the material in liquid or semi-liquid form so that the material is distributed over the surface and due to capillary attraction is drawn entirely or partially away from the points or tips of the roughened particles and accumulates at the bases of the projections. This leaves the ends of the projections free to extend into the connecting cement, free or partially so of the 10 coating material, so that they will engage 15 the cement or binding material between the parts. Since these projections are of considerably smaller area than the surface of the main body to which they are attached, a force or strain transmitted between the insulator parts so connected, or between a part 20 and the connecting cement will be concentrated in the projections. The projections being of elastic material and having a smaller section than the main body of the 25 insulator, the stress or strain between the connected parts which tends to disrupt them will be in inverse proportion to the cross-sectional area of the projections and will be directly proportional to their length. It is 30 evident then that if the projections are of sufficient length and of small enough cross-section, the internal strain or yielding stress between the connected parts can be almost entirely taken up by the projections, thereby 35 keeping down the stress in the main insulating members themselves.

When metal parts are assembled and attached to an insulating member, the connecting surfaces may be prepared and 40 treated the same way, but it is usually sufficient to simply roughen or groove the surface of the metal part so that a connecting cement will adhere firmly thereto, the yielding connection being provided at the 45 sanded surface of the insulating member, as above described.

When this invention is applied to an insulator in which one of the insulating members is interposed between metal parts, or is connected to a metal part, the connecting surfaces of the insulating member is prepared as above described. For example, the connecting surface of an insulating member 1 may be coated with a rather thick layer 50 of glaze 2, as shown in Fig. 5, in which particles 3 are placed before vitrifying, the glaze extending quite a distance or partially upon the sides of the particles, causing the particles to be quite rigidly held when the member so prepared, is vitrified. A coating of elastic or yielding material 4, such as wax or paraffin is then applied, the hollows between the points of the projections filling up by capillary attraction, leaving 55 the tips of the projections of the particles

free, or at least thinly coated with the yielding material, so that the tip will project into the connecting cement. If the glaze 2 is a thin coating, as shown in Fig. 6, the particles 3 will be less firmly held at the 60 base, and will therefore be more resilient, the elastic coating 4 then filling the spaces at the bases of the particles as before. Thus quite a wide variation can be produced by 65 changing the sizes of the particles, the 70 thickness of the coating of glaze, and the 75 yielding material.

If desired, this prepared surface can be extended entirely over the surfaces in contact with the cement, but there is no particular advantage in having more than the vertical sides of the insulating member thus prepared, and to sand the horizontal portion 5 would not materially increase the holding effect between the two parts, but in 80 order to preserve the elastic or yielding property, the elastic material or coating 4 can be extended over those surfaces which have no substantial gripping or holding effect.

When the connecting surface or surfaces of an insulating member 1 are thus prepared, or sanded, the insulating member is applied to a metal suspension cap 6 which is formed with a cup-shaped recess in which 95 a part of the insulating member is inserted, and the recess is preferably formed with an undercut groove 7 at the edge with internal holding ridges 8 at a distance from the edge and with a thin wall portion 9 at a 100 greater distance from the edge. The insulating member fits somewhat loosely within the suspension cap 6, and the connecting cement 10 is applied between the sanded surface of the insulating member and the 105 adjacent coöperating surface of the metal suspension cap 6, the cement engaging the projections of the particles 3 which extend above the yielding coating of the sanded surface previously described, or are thinly 110 coated.

In the same way a metal suspension pin 11 may be connected by means of cement 12 to an internal sanded surface 13 of the insulating member 1, as clearly shown in Fig. 1, 115 the pin having holding grooves 14 for the cement, and making a yielding connection with the insulating member through the sanded surface thereof.

Between the inner end of the suspension 120 pin and the insulating member is a pad 15 of yielding material, such as felt, paper, or the like, and between the edge of the metal suspension cap 6 and the adjacent surface 125 of the insulating member 1 is a ring or pad 16, also of elastic material, such as felt, paper, or the like, to protect the surface of the insulating member, and to prevent it from being checked or cracked due to the hardness 130 or contact of the metal cap, and also for

properly spacing the edge of the cap and the flange apart.

Instead of providing this pad or gasket 16, the lower edge of the metal cap may be 5 provided with a thick coating 17 of yielding material, as shown in Fig. 3, which will effectually space the insulating member 1 and the cap apart; or the adjacent surface 10 of the insulating member itself may be painted or coated with elastic or yielding material 18, as shown in Fig. 4, which serves the same purpose. In either case the formation of a bead or rim 19 offset on the outside of the edge of the cap does not form 15 a rigid strut between the cap and the insulating member, as the yielding material 17 or 18, or the pad 16, is also between the parts.

The advantage of insulators constructed 20 in accordance with this invention is that the projections formed are more or less resilient, which tends to relieve the main insulating members of stress which may be set up between them, the projections thus distributing the load or stress between the parts 25 since these projecting points tend to act as small elastic struts or springs of reduced cross-section, thereby deflecting readily under load and relieving the main insulator 30 parts of high stress at any particular point, the load being distributed by the yielding of the projecting points. This, of course, is very valuable where the insulator is subjected to changing temperatures, and by 35 varying the size and number of the projecting points and the coating material, it is readily seen that a wide range in inelasticity may be provided for, and insulators thus made are able to withstand the stresses due 40 to expansion and contraction with less frequent breakage.

This construction is particularly valuable where an insulating member composed of porcelain, or the like, is to be attached to a 45 suspension or connection member which is composed of a different material which has a different coefficient of expansion and contraction, such as a metal of which the suspension cap or pin would be constructed, 50 and it is very important that some yieldable connection be provided in an insulator which is made up of metal and porcelain parts in order that the more frangible insulating material may not be broken due to 55 the stress which would be imposed upon it by the harder or stronger metal, if there were no yielding or elastic connections between them.

I claim:—

60 1. In an insulator composed of a plurality of parts, a metal suspension cap, and an insulating member having coöoperating cementing surfaces, the insulating member having its cementing surface formed with 65 uneven unglazed projections extending above

a glazed surface and forming a substantially integral part of the member, a layer of yielding material reposing on the projections, and cement rigidly connecting the projections of the insulating member with the cementing 70 surface of the suspension cap so that a yielding action between the parts may be had due to the contact of the cement with the said projections.

2. An insulator comprising a plurality of 75 parts united by a cement interposed between adjacent surfaces, one of the parts being a metal part and another of the parts being composed of an insulating material which has its cementing surface formed with a 80 multiplicity of projections composed of material attached to the cementing surface by a vitreous glaze.

3. An insulator comprising a plurality of 85 parts, one composed of metal, with corresponding surfaces for uniting the parts, some of the uniting surface of one of the parts being provided with projections, yielding material applied to the projections and to the uniting surface which has no projections, 90 and cement connecting the said projections with the corresponding surface of the metal part.

4. An insulator comprising in combination 95 an insulating member having an extending flange and a projecting boss, a metal cap arranged to receive the boss and having its edge adjacent the flange of the insulating member, the cementing surface of the insulating member being formed with a multiplicity of projections composed of material attached to the cementing surface by a vitreous glaze, and a pad of yielding material interposed between the said adjacent edge 100 of the cap and the flange of the insulator. 105

5. An insulator comprising a plurality of connected parts, one comprising a metal cap, and another comprising an insulating member having a boss insertible in the cap with an extending flange disposed adjacent the 110 edge of the metal cap, parts having corresponding cementing surfaces and the cementing surface of the insulating part being provided with projections attached thereto, a coating of yielding material applied to the 115 cementing surface and projections of the insulating part cement rigidly connecting said projections with the corresponding surface of the other part to permit relative expansion and contraction of the parts, and a pad of 120 yielding material interposed between the adjacent edge of the cap and the flange of the insulator.

6. A plurality of metal parts separated by an insulating member having corresponding 125 surfaces for uniting the parts together, an insulating member having a portion of its corresponding surface provided with projections extending above and integrally attached to the surface by a layer of glaze, a 130

layer of yielding material reposing on the unroughened surface of the insulator member, and cement interposed between the corresponding surfaces of the parts for holding the parts together.

7. An insulator comprising an insulating member and a metal cap therefor, said insulating member having a portion of its surface adjacent said cap provided with a plurality of projections, cement interposed between said surface and said cap, and means for protecting the base portions of said projections from engagement with said cement.

8. In an insulator composed of a plurality of parts, a metal suspension cap, and an insulating member having coöperating cementing surfaces, the insulating member having its connecting surface formed with uneven projections extending above a glazed surface and forming a substantial integral part of the member, a layer of yielding material reposing on the projections and cement rigidly connecting the projections of the insulating member with the cementing surface of the suspension cap, so that a yielding action between the parts may be had due to the contact of the cement with the said projections.

9. An insulator, comprising a plurality of parts united by a cement interposed between adjacent surfaces, one of the parts being a metal part and another of the parts being composed of an insulating material which has its cementing surface formed with a multiplicity of projections composed of material attached to the cementing surface by a vitreous glaze, and yielding material applied to the roughened cementing surface.

10. An insulator comprising an insulating member and a metal cap therefor having corresponding surfaces for uniting the parts together, the insulating member having a portion of its corresponding surface provided with projections extending above and integrally attached to the surface by a layer of glaze, a layer of yielding material interposed between the unroughened surface of the insulating member and the corresponding surface of the metal cap and cement interposed between the corresponding surfaces of the parts for holding the parts together.

In testimony whereof I have signed my name to this specification on this 8th day of Aug., A. D. 1918.

ARTHUR O. AUSTIN.
